United States Patent Office

Des. 224,215
Patented July 11, 1972

224,215

VENDING STAND

Gary L. Baldwin, Oklahoma City, Okla., assignor to
SBI Incorporated, Phoenix, Ariz.

Filed May 12, 1971, Ser. No. 142,861

Term of patent 14 years

Int. Cl. D25—03

U.S. Cl. D13—1

FIG. 1

FIG. 2

FIG. 3

FIG. 4

FIG. 5

FIG. 6

FIG. 7

FIG. 8

FIG. 1 is a perspective view, showing my design;

FIG. 2 is a front elevation;

FIG. 3 is a side elevation;

FIG. 4 is a rear elevation;

FIG. 5 is a side elevation;

FIG. 6 is a top plan;

FIG. 7 is a horizontal section, showing the front and rear doors opened; and

FIG. 8 is a top plan prior to installation of roofing and ornamental grill.

The dotted lines in the several views are disclosed for illustrative purposes only and form no part of the claimed design.

I claim:

The ornamental design for a vending stand, as shown and described.
